UNITED STATES PATENT OFFICE.

ABRAM NELSON, OF NEW YORK, N. Y.

STAPLE.

SPECIFICATION forming part of Letters Patent No. 319,607, dated June 9, 1885.

Application filed July 9, 1883. (No model.)

To all whom it may concern:

Be it known that I, ABRAM NELSON, a citizen of the United States, residing at New York, in the county of New York and State 5 of New York, have invented a new and useful Improvement in Staples, of which the following is a description.

This invention is an improvement in hook-staples intended especially for binding the 10 strands of wire fences to the post or framing; and it consists in certain features of construction, which will be hereinafter described and claimed.

In the drawings, Figures 1 and 2 are perspective views of my staple, the latter having 15 the body notched at the vertices of its angles.

Heretofore hook-staples have been made comprising a body and a hook, the body being serrated transversely on one or more of its 20 sides, and having its point drawn to a chisel-edge.

My improved staple consists of a body, A, and a hook, B. The body A is made equilateral and rectangular in cross-section, and 25 has its extremity b formed to what, for convenience of reference, I term a "needle-point." This point is formed by drawing the sides gradually and equally downward, so that said point b will lie in the axial center of the body.

30 On one side of the body A, near its upper end or head, B, I form a shoulder, a, which faces toward the needle-point, as shown. The hook C has its shank united with the body at a point slightly above the shoulder a, as shown. This shoulder a provides a better seat for the 35 wire, and operates to prevent the staple being driven so far into the post or other support as to embed the wire therein, and so tend to cut or fracture the wire by acutely bending it, as 40 will be understood from the drawings.

The hook C, I form circular in cross-section, so it will not bend in driving, and in case it should strike a knot or other obstruction it will be forced directly through it, whereas 45 any angular formation would give the hook a tendency to veer off in one direction or another.

In the use of a chisel-pointed body the staple needs be driven into the post or other support relatively to the direction of the grain there- 50 of, so that the hook will be necessarily in line with the grain. By my improvement the staple

may be driven independently of the grain of the wood of the support, so that the hook may be arranged vertically, horizontally, or at any intermediate angle desired.

55

Another important advantage in the form of my staple-body over the chisel-pointed one is that the latter when driven into a support spreads the timber, and in a short time water entering the cracks so made will rust the body 60 and cause it to become loose in a short time, so that a little strain upon the wire will withdraw the staple, whereas in my form of body the timber closes snugly against it on all sides.

I prefer, in order to give the body a stronger 65 frictional hold, to notch it at the vertices of its angles, the remainder of its surface remaining smooth, so that the body may be easily driven. These notches a', it will be seen, distinguish 70 from the serrations extending transversely of the sides of the body, and are advantageous thereover in the following respect: The serrations tend to weaken the body at the cross-sectional point where they are formed, whereas the notches produce no appreciable weakening of the part, and at the same time operate to add the desired friction to the body. To further avoid any weakening of the body by reason of these notches, I stagger them—that 75 is, form the notches in each edge or vertex alternately with those in the adjacent ones—and am thus able to get the maximum degree of friction with the maximum strength, and I avoid all possibility of bending of the body 80 while being driven—an objection which lies to 85 those staples serrated transversely across one face.

I am aware that staples formed with bodies and hooks are not new; also, that such bodies have been formed rectangular in cross-section, 90 and have had one or more of their faces serrated transversely, and I do not claim such construction as my invention; but,

Having thus described my invention, what I claim as new is—

95

1. The improved staple comprising the body made equilateral and rectangular in cross-section, and having its lower extremity drawn to a needle-point located in the axial center of the body, the said body being formed on one 100 side with a shoulder, a, near its upper end or head, and the hook made circular in cross-

section, and having its shank united to the body at a point slightly above the shoulder a , substantially as and for the purposes specified.

2. As a new and improved article of manufacture, a hook-staple consisting of the body A, made rectangular in cross-section, and having its lower extremity drawn to a needle-point, and having the vertices of its angles notched, the notches of each angle alternating with those of the adjacent ones, and formed

on one side, near its upper end or head, with a shoulder, a , and the hook made round in cross-section, and having its shank united with the body at a point slightly above the shoulder a , substantially as set forth.

ABRAM NELSON.
